CLAIM

The ornamental design of a novelty horn, as shown and described.

DESCRIPTION

FIG. 1 is a perspective view of a novelty horn that depicts a wedge of cheese, in this embodiment having smooth sides, indentations formed into the top and bottom, and a sharp-edged cylindrical mouthpiece;

FIG. 2 is a top plan view of the novelty horn of FIG. 1;

FIG. 3 is an end elevational view showing the interior of the novelty horn of FIG. 1;

FIG. 4 is a bottom plan view of the novelty horn of FIG. 1; FIG. 5 is an end elevational view distinctly showing the placement of the mouthpiece of the novelty horn of FIG. 1; FIG. 6 is a side elevational view of the novelty horn of FIG. 1;

FIG. 7 is a side elevational view of the novelty horn of FIG. 1;

FIG. 8 is a perspective view of a novelty horn that depicts a wedge of cheese, in this embodiment having indentations formed into its sides, top, and bottom and a cylindrical mouthpiece having a hemispherical end;

FIG. 9 is a top plan view of the novelty horn of FIG. 8;

FIG. 10 is an end elevational view showing the interior of the novelty horn of FIG. 8;

FIG. 11 is a bottom plan view of the novelty horn of FIG. 8;

FIG. 12 is an end elevational view distinctly showing the placement of the mouthpiece of the novelty horn of FIG. 8;

FIG. 13 is a side elevational view of the novelty horn of FIG. 8;

FIG. 14 is a side elevational view of the novelty horn of FIG. 8;

FIG. 15 is a perspective view of a novelty horn that depicts a wedge of cheese, in this embodiment having smooth sides, indentations formed into the top and bottom, a sharp-edged cylindrical mouthpiece, and a necklace strap;

FIG. 16 is a top plan view of the novelty horn of FIG. 15; FIG. 17 is an end elevational view showing the interior of the novelty horn of FIG. 15;

FIG. 18 is a bottom plan view of the novelty horn of FIG. 15;

FIG. 19 is an end elevational view distinctly showing the placement of the mouthpiece of the novelty horn of FIG. 15; FIG. 20 is a side elevational view of the novelty horn of FIG. 15;

FIG. 21 is a side elevational view of the novelty horn of FIG. 15;

FIG. 22 is a perspective view of a novelty horn that depicts a wedge of cheese, in this embodiment having indentations formed into its sides, top, and bottom, a cylindrical mouthpiece having a hemispherical end, and a necklace strap;

FIG. 23 is a top plan view of the novelty horn of FIG. 22;

FIG. 24 is an end elevational view showing the interior of the novelty horn of FIG. 22;

FIG. 25 is a bottom plan view of the novelty horn of FIG. 22;

FIG. 26 is an end elevational view distinctly showing the placement of the mouthpiece of the novelty horn of FIG. 22; FIG. 27 is a side elevational view of the novelty horn of FIG. 22;

FIG. 28 is a side elevational view of the novelty horn of FIG. 22;

FIG. 29 is a perspective view of a novelty horn that depicts a wedge of cheese, in this embodiment having smooth sides, indentations formed into the top and bottom, a cylindrical mouthpiece having a hemispherical end, and a necklace strap;

FIG. 30 is a top plan view of the novelty horn of FIG. 29; FIG. 31 is an end elevational view showing the interior of the novelty horn of FIG. 29;

FIG. 32 is a bottom plan view of the novelty horn of FIG. 29;

FIG. 33 is an end elevational view distinctly showing the placement of the mouthpiece of the novelty horn of FIG. 29;

FIG. 34 is a side elevational view of the novelty horn of FIG. 29; and,

FIG. 35 is a side elevational view of the novelty horn of FIG. 29.
